Primary Examiner—James Gandy*Assistant Examiner*—Carol Rademaker*Attorney, Agent, or Firm*—Gerald R. Boss, Esq.; Troutman Sanders LLP[57] **CLAIM**

The ornamental design for a pillowed wing, as shown and described.

DESCRIPTION

FIG. 1 is a rear view of a pillowed wing showing my new design;

FIG. 2 is a side view of a pillowed wing showing my new design, it being understood that the opposite side is a mirror image thereof;

FIG. 3 is a front view of a pillowed wing showing my new design with portions of the broken line illustration of the doll omitted for clarity of illustration; and,

FIG. 4 is a top plan view of a pillowed wing showing my new design.

The broken line showing of a doll is for illustrative purposes only and forms no part of the claimed design.
